UNITED STATES PATENT OFFICE.

EARL RAY HEATH, OF COLUMBUS, OHIO, ASSIGNOR TO THE INTERNATIONAL TELEPHONE COMPANY, OF COLUMBUS, OHIO, A CORPORATION OF OHIO.

PARTY-LINE TELEPHONE.

Application filed June 10, 1924. Serial No. 719,215.

This invention relates to improvements in party line telephone systems, one object of the invention being the provision of a system by means of which in party line service a series of stations will be connected to the exchange and provided with apparatus whereby upon the impression of a positive potential upon the line, all substations will be disconnected from the line, i. e., the talking and listening facilities of the instrument. Then, and because of the fact that the substations herein described are fitted with either the "harmonic" or "synchromonic" ringers, a particular frequency of alternating current, having an affinity only for one particular substation ringer, is impressed upon the line, said alternating current ringing the bell of the substation desired, the ringer itself serving a dual purpose: that of (a) ringing the bell, and (b) acting as a half wave rectifier of the alternating ringing current, which resultant unidirectional current then is passed through a "drop" relay, ("F" in Fig. 1^b), which connects the particular substation signalled. This particular feature is of the greatest importance; as, first of all, by the simple application of a positive potential to the line, all transmitters and receivers are disconnected from the line, and then, by the application of a ringing current, the substation desired is both signalled and connected with the one operation.

In order to fully understand the invention there will be illustrated and described at the present time one method of putting the same into effect and in which Figure 1 is a diagrammatic view of the calling cord.

Figure 1^a is a similar view of the answering cord, and

Figure 1^b is a diagrammatic view of a substation, it being understood that a plurality of the same may be connected to the line and that all three of these figures are to be considered jointly as the complete system.

In order that the present invention may be more fully understood the description following will be set out in various stages and under sub-topics according to the operation to be accomplished.

It might be said that the special apparatus referred to above and more particularly set forth later on comprises essentially an assembly of a polarized relay and condenser,

a pair of interlocking relays, and a frequency ringer serving as a rectifier of the ringing current for actuating one of these relays.

There is an assembly of four contact springs 59, 60, 104 and 109, on the polarized relay E, and when a pulsing voltage of a negative polarity is applied, the relay is operated in the direction indicated C, which closes contact springs 59 and 104 and 60 and 109. If the opposite or positive polarity be applied the relay operates toward the opposite direction indicated D, which closes contact springs 59 and 60.

There is also an assembly of four contact springs 11, 12, 78 and 79 mounted upon the interlocking relays F and H. Springs 11 and 12, and 78 and 79 are normally closed. These contacts close the talking circuits of the instruments. The disconnect relay H operates to open these contacts. Relay F, the connecting relay, operates to release the action imposed by the operation of relay H.

There is a reciprocating action among the three mentioned relays, E, F and H. If the receiver K be on the hook 15 at a time when a negative pulse is applied, relay F will be operated. On the contrary, if the receiver be off the hook when a negative pulse is applied, relay H will be operated. If a positive pulse be applied to relay E, armature E' will be deflected in the direction D; and if the receiver be on the hook, relay H will be operated; there will be no action when the receiver is off the hook, and relay E operated to the direction D.

The ringers M of all instruments are permanently connected across the lines and they are of the harmonic or synchromonic type, the frequencies being the standard frequencies in common use; as 16, 30, 42, 54 and 66 cycles per second.

The harmonic or synchromonic method of ringing thus being employed, there is mounted upon each ringer an assembly of two contact springs 113 and 114, one of which is mounted fast to the armature and is subject to the motion of same; this armature (being an integral part of the ringer and therefore, electrically stating, a part of the frame, and the frame connected to that side of the line on which the ringing current is impressed) through its rhythmic vibration, then passes a half wave unidirectional cur-

rent, obtained from the alternating ringing current, out through the two contacts above enumerated to actuate the "drop" relay F.

A general outline of this system follows:

A receiver K is removed from its hook 15 at a certain substation S Fig. 1^b. The signal lamp L glows at the switchboard; operator answers by plugging in and a positive pulse 10 is sent out automatically over the line. Relay E is operated in the direction D on all instruments. On the calling station there will be no movement except the deflection of relay E. In this manner all idle stations 15 will be locked out.

Upon the completion of service, when the receiver is placed upon the hook, a negative pulse is sent out over the line. This pulse deflects relay E the direction C and operates 20 relays F of all instruments, preparing them for the next call.

On all outgoing calls from the exchange, a positive pulse is automatically sent out upon inserting answering plug P in the socket 25 S. This pulse disconnects all instruments as previously explained and the operator only presses ringing key of particular frequency desired; which frequency, while ringing the bell of station desired, serves to 30 operate relay F of that station, by means of the contact springs aforementioned, thus connecting the lines through to the talking and listening circuits of the instrument. The connecting of all instruments to the line is 35 made automatic upon completion of service. In case the calling party should hang up before called party answers, the former controls this restoring action; otherwise each 40 party controls the separate functions of the line involved.

A restoring key P² is also provided for emergency use by the operator.

A detailed explanation of the various circuits will now be taken up.

45

Subscriber calls operator.

Upon the removal of the receiver from the hook 15, the hook switch contacts are closed 50 in the usual manner and current flows from negative battery B¹, the conductor 1, line relay J', the conductor 2, the contacts 3 and 4 of relay J, the conductor 5, ring 6 of jack socket S, line 7, the conductor 8, the winding 55 9, of induction coil 9', the conductor 10, the contact springs 11 and 12, the conductor 13, hook switch contacts 14 and 15, the conductor 16, transmitter 17, the conductor 18, conductor 19, line 20, tip 21, the conductor 60 22, and contact springs 23 and 24 of relay J, the conductor 25 to grounds G and G' and positive battery B'. This circuit energizes line relay J' which lights the line lamp L from negative battery B¹, the conductor 26, 65 line lamp L, the conductor 27, contact

springs 28 and 29 of relay J', the conductor 30 to grounds G and G'.

Operator plugs in.

The line lamp L glows, and the operator 70 plugs in, and current flows from negative battery B², the conductor 31, winding 32 of relay B, the conductor 33, coil of relay A, the conductor 34, sleeve 35 of plug P', sleeve 36 of jack socket S, the conductor 37, cut-off relay coil J, the conductor 38 to grounds G and G⁵. This current energizes relay J, clearing the line at contacts 3 and 4 and 23 and 24. It also energizes supervisory relay A which prepares the way for the preliminary pulse to follow, and the supervisory circuits. It does not, however, energize relay B on account of an insufficient number of turns in the winding 32 of the relay. There is another winding 47 on relay B 85 through which it will be energized, i. e., the path of the preliminary pulse. At the moment of the inserting of the plug, current flows from plus contact 39 of rectifying relay R, the conductor 40, the contacts 41 and 42 of relay C, the conductor 43, the contacts 44 and 45 of relay A, the conductor 46, winding 47 of relay B, the conductor 48, contacts 49 and 50 of relay B, the conductor 51, tip 52 of plug P', tip 21 of jack socket S, line 95 20, the conductor 53, condenser 54. To oppose this charge upon the plates of condenser 54, a negative pulse flows from ground 9², the conductor 55, relay E, the conductor 56, to condenser 54. This pulse deflects relay E in the direction D, closing contact springs 59 and 60 and as the pulse divides at the junction of the conductors 20 and 53, it follows the conductor 19, the conductor 18, transmitter 17, the conductor 16, hook 105 switch contact 15, and from hook contact 15 to contact 57, the conductor 58, springs 59 and 60 of relay E now closed, conductor 61, relay H, the conductor 62, the conductor 63. This circuit as will be seen simply places relay coil H electrically in series with relay E; bridging the condenser for the moment of pulsing. The relay coil H will be energized momentarily and raises spring 11 to be engaged by the projecting hook F' of the 115 relay F, which disconnects the talking and listening circuits of all the instruments whose receivers were not off the hook at the moment of pulsing.

At the instrument where the call was made 120 and the receiver off the hook there can be no action other than a deflection of armature E', consequently the instrument remains connected to the line for its duration of service. This pulse flowing through 125 winding 47 of relay B, energizes this relay; but the springs being relatively stiff, retard this action somewhat allowing an appreciable period to elapse from the moment of the contacting of contact 52 with contact 21, 130

to the breaking of contacts 49 and 50. This period determines the length of the preliminary pulse; and while the circuit through this winding 47 of coil B is broken, the 5 armature is now sufficiently close to the coil that the small current flowing in winding 32 will be enough to complete the stroke and close the lines through to the talking circuit of the cord. As follows:—contacts 50 and 10 64 of relay B, the conductor 65, winding 66, relay D, conductor 67 to g^7 or positive battery B^3 and for the tip side of line; negative voltage of battery B^3 , the conductor 68, winding 69 of relay D, conductor 70, contacts 15 71 and 72 of the relay B, the conductor 73, ring 74 of plug P' to ring 6 of jack socket S for the other line; and to repeat, current flows as follows:—the contact 6, the conductors 7 and 8, the induction coil 9, 20 the conductor 10, the contacts 11 and 12, now closed, the conductor 13, the contacts 14 and 15, the conductor 16, the transmitter 17, the conductors 18, 19 and 20, the contacts 21 and 52, the conductor 51, and the contacts 25 50 and 64. The voice current arriving at coil 9 of induction coil 9', is induced in the other winding 81 of the coil 9', and the voltage generated in this winding is impressed upon the receiver K, the circuit of 30 which is closed by hook switch contacts 14 and 75, the conductor 76, receiver K, the conductor 77, spring contacts 78 and 79 of the relay H, the conductor 80, induction coil winding 81, conductor 82, condenser 83, and 35 conductor 84.

Supervision.

Relay A on being energized, closed a pair of contacts 86 and 87 which prepared the 40 way for the supervisory lamp L^2 ; as follows:—ground g^4 , the conductor 85, the contacts 86 and 87 same relay, the conductor 88, the contacts 89 and 99 of relay D, the conductor 91, supervisory lamp L^2 , to the negative battery B^4 and ground G^6 . This circuit is broken at contacts 89 and 99 of 45 relay D if the receiver is off the hook, and the lamp L^2 extinguished, by this means.

The current flowing through windings 66 and 69 of relay D supplying the battery B^3 to the line, energizes this relay and besides clearing the supervisory signal lamp L^2 , closes a circuit from negative side of battery B^3 , the conductors 68 and 91, contact springs 92 and 93, the conductor 94, relay C, the conductor 95 to ground g^5 . This energizes the relay C, which prepares the way for the pulse which must be applied to the tip of line after the completion of service. 50 It reverses the polarity of current to be sent out after the subscriber hangs up. It breaks the positive pulse from its point of contact with the line (at 49) by breaking contacts 42 from 41 and closing negative pulse at its 55 point of contact 49 with the line by clos-

ing contact 42 with contact 96 which is the negative terminus of the pulsing voltage originating at contacts 98; as, contacts 98, conductor 97 and the contact 96.

70

Operator answers.

75

The operator throws the listening key H^1 , which connects her listening set across the line and inquires for the number. This being given, a calling cord, Fig. 1, (the mate of the answering cord used) is inserted into the jack S, Fig. 1^a, as requested. Current now flows from the battery B^6 , the conductor 131, winding 132 of relay C², the conductor 133, relay C¹, the conductor 134, sleeve 135 of plug P, sleeve 36 of jack socket S to cut off relay coil J as previously explained. This energizes relay C¹, the same as relay A in the answering cord and similar circuits apply. The effect on relay C² is the same as on the relay B in the answering cord. Current now flows from positive contact 39 of relay R', the conductor 140, contacts 141 and 142, the conductor 143, contacts 144 and 145, the conductor 146, coil 147, the conductor 148, contacts 149 and 150, the conductor 151, tip 152, to tip 21 of line jack socket S, and out over the called line as follows:—conductors 20 and 53, condenser 54. The opposite charge flows from ground g^2 , conductor 55, relay E, conductor 56, and condenser 54. The relay E is deflected in the direction of arrow D closing contact springs 59 and 60 which places relay H in series with the relay E as before. This pulse locks out all stations on the line.

80

85

90

95

100

To select a given one, a button O corresponding to the frequency necessary to ring the bell, is pushed. This frequency having 105 the same period as the ringer of the station requested, causes the bell of the called station to ring. When the armature of the bell has reached its maximum stroke, contacts 113, 114 are periodically closed, and 110 an unidirectional current flows.

115

The resultant force, upon which the particular instrument selected depends for its connection, is taken from the alternating ringing current generator G, as follows: generator G, the conductor 117, contact springs 118 and 119 of ringing button O, the conductor 170, contacts 171 and 172 of relay C², the conductor 173, ring 174 of plug P, contacts 6, of jack socket S, the conductors 7, 110 and 112, spring contacts 113 and 114, conductors 115 and 106, the relay F, conductors 107, 63 and 56, condenser 54, conductors 53 and 20, contact 27, jack socket S, tip 152 of plug P, the conductor 151, contacts 150 and 164 of relay C², the conductor 165, contacts 116 and 120 of button O, and conductor 121, to g^9 . This unidirectional current operates relay F and causes it to 125 release the hook F' which allows the ten-

130

sion in spring 11 of the relay H to close the contacts 11 and 12, and 78 and 79.

It is to be noted that these spring contacts will be closed only on the instrument selected; all others will remain locked out until service is completed.

Called party responds.

When the called party answers, the circuit 10 is completed from negative voltage of the battery B^5 as follows: the battery B^5 , the winding 169 of relay C^4 , the conductor 170', the contacts 122 and 123 of key P^2 , the conductor 124, the contacts 125 and 119 of the 15 button O, the conductor 170, contacts 171 and 172 of relay C^2 , the conductor 173, contacts 174 and 6, the conductors 7 and 8, coil 9, the conductor 10, contacts 11 and 12, the conductor 13, contacts 14 and 15, the conductor 16, transmitter 17, the conductors 18, 19 and 20, contacts 21 and 152, the conductor 151, contacts 150 and 164, the conductor 165, contact springs 116 and 126 of button O, the conductor 127, contact springs 128 and 129 25 of key P^2 , the conductor 130, winding 166 of relay C^4 to positive battery B^5 . This energizes the relay C^4 and breaks the circuit of the calling supervisory lamp L' at contacts 189 and 190. It also closes a circuit from 30 negative side of the battery B^5 , the conductor 191, the contact springs 192 and 193 of relay C^4 , the conductor 194, the relay C^3 , the conductor 195 to g^7 ; energizing the relay C^3 , which prepares the way for the pulse 35 which must be applied to the tip of line after the completion of service. It opens the positive pulsing potential from its point of contact with the line at the contacts 149 and 150, by opening the contacts 142 and 40 141, and closes the negative pulsing voltage to its point of contact with the line, by closing contacts 142 and 196, this being the negative terminus of the pulsating voltage originating at the contacts 98, 97, 197 and 45 196.

Called subscriber hangs up.

Upon the completion of service the subscriber places the receiver upon the hook. 50 This action opens the circuit through the relay C^4 . Contacts 192 and 193 are opened by this action and contacts 192 and 199 are thereby closed; and as coil C^3 is a slow releasing coil its armature is retained 55 momentarily. Therefore negative current will flow momentarily from the battery B^5 , the conductor 191, the contacts 192 and 199 of relay C^4 , the conductor 200, the contacts 201 and 202 of the relay C^3 , the conductor 203 and conductor 133. This action places 60 negative potential on both sides of the energized winding of the relay C^2 and this relay C^2 releases. In doing so, its contact 150 closes with 149; and current follows this 65 path:—the conductor 148, coil 147, the con-

ductor 146, the contacts 145 and 144 of the relay C' , the conductor 143, the contacts 142 and 196 of the relay C^3 , to negative potential of R' . By this time the relay C^2 has become reenergized thus breaking the contacts 149 and 150. Relay C^3 also has released, but a moment later, however. So the negative pulse had already gone to connect the instruments, as follows:—negative of relay R, the contact 98, the conductors 75 97 and 197, contacts 196 and 142 of the relay C^3 , the conductor 143, the contacts 144 and 145 of the relay C' , the conductor 146, the winding 147, the conductor 148, and the contacts 149 and 150 of the relay C^2 , the conductor 151, tip 152, contact 21, the conductors 20 and 53, condenser 54, conductor 5, relay E, and ground G^2 . The armature of the relay E is now deflected toward C. Therefore the current flows from conductors 80 20, 19 and 18, transmitter 17, the conductor 16, contacts 15 and 57, conductors 58, springs 59 and 104, conductors 105 and 106, the relay F, conductors 107 and 63, to conductor 56, thus energizing the relay F which closes 90 the station circuits at the contacts 11 and 12 and 78 and 79.

Subscriber hangs up (calling).

The action of the answering cord upon the hanging up of the receiver by the calling party is identical with that of the calling cord and need not be taken up here. There is a contingency however, when the calling party may hang up before called party has answered, and this contingency must be taken care of. In order to do this a pair of contacts have been placed upon each of the relays D and C, Fig. 1^a; so that when the calling party hangs up a positive potential may be momentarily applied, as follows:—the ground g^8 , the contact springs 104 and 105, Fig. 1^a, the conductor 106, the contacts 107 and 108 of the relay C, the conductors 109 and 170', and the coil 169 of the relay C^4 , Fig. 1, the conductor 169' to negative side of battery B^5 . This merely serves to energize the relay C^4 so that it may function as if a receiver had really been removed. This energization is made only from the energizing of the contacts 104 and 105 of the relay D and until the "break" of the contacts 107 and 108 of the relay C takes place.

Disconnecting party who failed to hang up the receiver.

In order to clear a line from the action of a subscriber who has left the receiver off the hook, a key is provided in the cord circuit. 125 This key is shown in the accompanying drawings as key P^2 . When the key P^2 is operated, a negative pulse, originating at the relay R', the contact 98, the conductors 97 and 197, contacts 204 and 128 of the key 130

P², the conductor 127, the contacts 126 and 116, the conductors 164, contacts 165 and 150, the conductor 21, contacts 152 and 151, the conductors 20, 19 and 18, transmitter 17, 5 the conductor 16, contacts 15 and 14, conductor 13, contacts 109 and 60, the conductor 61, the relay H, conductors 62 and 63, the relay E, conductor 55 to the ground g². This energizes the relay H and disconnects 10 the instrument at the contacts 11 and 12, and 78 and 79.

Signal station with receiver off hook.

The station then may be signaled by using 15 the correct ringing frequency required by the ringer as the line is now clear, and the bell will be rung before the springs 113 and 114 have contacted to energize the relay F as before stated.

20 What I claim as new is:

1. In a party line telephone system, including an exchange station and substations, a ringer at each substation, means at the exchange station for impressing upon the 25 line an alternating current of a frequency having affinity for a ringer at a selected substation, whereby said ringer will operate to ring its bell and also act as a half-wave rectifier of the alternating ringing current, 30 and means operable by the resultant unidirectional current to connect the particular substation signaled.

2. A party line telephone system, including means operable by the insertion of a 35 plug to disconnect all substations from the line, and means to send out on the line impulses of a predetermined character and means operable by such impulses to connect only a selected substation to the line.

40 3. A party line telephone system, including means operable by the insertion of a plug to disconnect all substations from the line, and means to send out on the line impulses of a predetermined character and means 45 operable by such impulses to connect only a

selected substation to the line, said last-mentioned means being operable to send out on the line an impulse having a characteristic different from that of the first-mentioned impulse.

4. A party line telephone system including an exchange and a plurality of substations, a polarized relay, a pair of interlocking relays, a frequency ringing connector, and cooperating means for said relays in each substation, means located in the exchange station for impressing upon the line an electrical current of one characteristic and cooperable with polarized relays in all substations to disconnect the substations 55 from the line, and a second means in the exchange station for impressing upon the line an electrical current of different characteristic and having an affinity for a particular frequency ringing connector and co-60 operable with the latter, whereby one substation is connected at a time.

5. In a party line telephone system including an exchange station and a plurality of substations connected in line, a polarized 70 relay, a pair of interlocking relays, a frequency ringing connector and cooperating means for said relays, in each substation, a cord circuit including a plug and socket at the exchange station, two sources of electricity of different characteristics located at the exchange station, means for connecting one of said sources with the polarized relays at the substations, whereby a single impulse is sent out on the line to operate 75 said last-mentioned relays to disconnect the substations from the line, and means located at the exchange station for controlling the operation of the ringing connectors, whereby a particular frequency ringing connector is 80 actuated at a selected substation to connect the same to the line.

In testimony whereof I affix my signature.

EARL RAY HEATH.
